UNITED STATES PATENT OFFICE

ALBERT KAMRATH, OF ST. LOUIS, MISSOURI

FOOT WARMER

Application filed March 13, 1930. Serial No. 435,504.

This invention relates broadly to devices for warming the feet during cold weather, and the primary object of the invention is to provide certain new and useful improvements in foot warmers, one of the main objects of the invention being to provide a warmer of this character which is comparatively simple in construction, may be manufactured and retailed at a nominal cost, is practical, and otherwise well adapted for the purpose designed.

Other objects and advantages of the invention will become apparent during a study of the following description, taken in connection with the accompanying drawings, wherein:

Figure 1 is a perspective view of my improved foot warmer.

Figure 2 is a detail sectional view, taken substantially on the line 2—2 of Figure 1.

Figure 3 is a similar view, taken substantially on the line 3—3 of Figure 1.

With reference more in detail to the drawings, it will be seen that my improved foot warmer comprises a main body or casing, designated generally by the reference character C, the said casing C comprising a bottom 5, consisting of an outer layer of fabric 6, the outer layer of fabric 6 being preferably gingham, and an inner layer of wool cloth 7. Between said inner and outer layers 6 and 7 is a filling, preferably of cotton batting 8. The casing C comprises further a peripheral wall 9, of a material corresponding to the material of the outer layer 6. The wall 9 rises from the bottom 5, and stitching 11 secures the lower edge of the wall 9 and the marginal edges of the inner and outer layers 6 and 7 together, as clearly disclosed in Figure 2. A top wall 10, at its marginal edge, is stitched to the upper edge of the peripheral wall 9, as at 12. The top wall 10 is provided with a pair of suitable openings 13—13. A reinforcing annulus 14 of leather, or any other suitable material is folded upon itself, in a manner clearly suggested in Figures 2 and 3, and provides an annular channel for receiving the edge of the top wall 10, at the opening 13.

Arranged within the outer casing C is a pair of foot forms or boots, designated generally by the reference character 15. One boot 15 is provided for each opening 13. Each of the boots 15 is preferably formed of wool cloth, and comprises a toe portion 16, a heel portion 17, and a leg portion 18. The leg portion 18 is of course, open at its top for receiving the foot of the wearer, and at its upper opened end, the leg portion 18 is stitched to the annular reinforcing member 14, which reinforcing member 14 is in turn stitched to the top 10 through the medium of stitching 19. The sole of the boot is designated by the reference character 20 and the soles 20 of the boots, are preferably formed from woolen material of suitable thickness, the soles 20 resting on the inner layer 7 of the bottom 5, of the casing. Within the space between the peripheral wall 9 of the outer casing C and the boots 15 and also arranged between the boots, is a filler of cotton batting 8'.

In actual practice, both feet of the user are inserted through the respective holes 13 to be received, each by a boot 15, and it is apparent that in view of the fillers 8 and 8', a heavy and warm covering is formed for the feet.

Even though I have herein shown and described the preferred embodiment of my invention, it is to be understood that the same is susceptible to changes fully comprehended by the spirit of the invention as herein described, and the scope of the appended claim.

What is claimed is:

A foot warmer comprising a casing including a bottom wall, a top wall, and a peripheral wall connecting said top and bottom walls, said bottom wall comprising spaced inner and outer layers of fabric, a filling material arranged in the space between said inner and outer layers of fabric, said top wall being provided with a pair of leg accommodating openings, a pair of separable boots arranged in said casing and supported on said inner layer of fabric, said boots at their upper ends registering with said leg accommodating openings, 100

means for securing the upper edges of said boots to said top wall at the edge of the respective leg accommodating openings, and filling material arranged between said boots, 5 and between the boots and peripheral wall of the casing for substantially enveloping the boots.

In testimony whereof I affix my signature.
